UNITED STATES PATENT OFFICE.

DANIEL GOFF, OF MILLVILLE, NEW JERSEY.

DISTRIBUTOR FOR COMMUNICATED OR PULVERULENT FUEL

1,318,375.

Specification of Letters Patent. Patented Oct. 14, 1919.

Application filed August 17, 1918. Serial No. 250,264.

To all whom it may concern:

Be it known that I, DANIEL GOFF, a citizen of the United States, residing at Millville, in the county of Cumberland, State of New Jersey, have invented a new and useful Distributor for Communited or Pulverulent Fuel, of which the following is a specification.

My invention relates to a device for distributing comminuted or pulverulent fuel in a furnace, and consists of a novel construction of the same, and appurtenances connected therewith whereby the fuel is caused to be consumed more perfectly and there is an intensification of the heat resulting therefrom.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a side elevation of a fuel distributor embodying my invention including also a side elevation of a steam boiler, the casing therefor, and the furnace for the boiler.

Fig. 2 represents a front elevation thereof.

Fig. 3 represents a vertical section of the distributor on line 3-3 Fig. 4, on an enlarged scale.

Fig. 4 represents a horizontal section on line 4-4 Fig. 3.

Fig. 5 represents a section similar to Fig. 4 showing the addition thereto of steam supplying pipes.

Similar numerals of reference indicate corresponding parts in the figures.

Referring to the drawings—

1 designates a steam boiler, and 2 designates the casing therefor. 3 designates the furnace for the boiler, and 4 designates the bridge wall, which features of themselves being well known in the art.

5 designates a hopper for containing comminuted or powdered fuel, the same being supported adjacent to the front wall of the casing and having at its discharge end the chute 6 which is adapted to enter said wall and be placed in communication with the furnace 3 in the opening 7 in said wall.

Within the furnace is the distributor 8 for the fuel, the same consisting of the vertically arranged main side deflectors 9 formed of plates on whose terminals are sleeves in which are fitted the vertically extending

tubes 10, the upper and lower ends of the latter being secured in openings in the walls 11 of the distributor 8, it being noticed that the distributor comprises somewhat of a box 80 which is firmly secured within the furnace and located at the adjacent portions of the front wall of the furnace at the inner terminal of the chute 6, whereby the latter is in communication with the interior of the distributor.

The deflectors are formed of plates extending flaring from about the center of the distributor to the sides of the latter forming between them the passages 12 which are 70 open at their opposite ends so that their inner ends receive the fuel directed to the same, and their outer or side ends discharge the fuel into the furnace.

The deflectors at the inner terminal of 75 the distributor are united at their forward ends forming an auxiliary V-shaped member preserving, however, the passages 12 at the right and left of the same.

In the chute 6 is the nozzle 13 with which 80 is connected the pipe 14, the latter being attached to the casing of a blowing apparatus 15, whereby air may be directed from the latter through the pipe 14 into the nozzle 13, and injected from the latter through the 85 chute 6 into the distributor box, it being evident that the comminuted or pulverulent fuel entering the chute from the hopper will be engaged by the blast of air and so be blown forcibly into said distributor box, the fuel when, owing to the deflectors, will be discharged through the passages 12 into the furnace in somewhat disintegrated condition, without impacting or matting, and so it is supplied loose to the 90 furnace.

The distributor box is surrounded at the top and bottom by the water jackets or headers 16 which are connected with the walls 11 of the former, said jackets or headers 160 being in communication by the tubes or flues 10, one of the jackets having a supply pipe 17, and the other jacket having a discharge pipe 18, it being evident that running water may flow through the jackets 105 and tubes to prevent burning-out of the same.

Entering the furnace is the nozzle 19 of the pipe 20, the latter being in communication with a source supply of hot air which 110 is forcibly injected into the furnace and directed above the grate thereof, it being seen

that I employ a bed of large hard coal on the grate and supply the comminuted or pulverulent fuel over said bed in the loose condition stated, the hot air serving also to blow 5 apart or disintegrate said fuel to a greater extent and supply the fuel with said hot air, whereby the combustion of the fuel is carried on to a greater extent and so rendered more perfect, highly intensifying the heat 10 thereof.

In Figs. 1 and 5 I show the employment of pipes 21 to admit steam to the distributing box, the steam commingling with the fuel and so serving to increase combustion 15 and the further intensification of heat resulting from the steam.

It will be seen that the deflectors 9 while being preferably curved, as shown, extend in radial directions from about the center 20 of the distributor laterally outwardly therefrom, consequently the fuel directed into the intervening passages 12 is blown in various streams into the space of the furnace, effectively filling the same, and is so agitated 25 and aerated that it will be in somewhat loose condition therein over the bed of coal, its combustion thus being accelerated, producing a high degree of heat as is evident.

I find that it is advantageous to place a 30 bed of large hard coal on the grate, and when it is burning the pulverulent fuel is introduced over the same, whereby the fuel is more rapidly consumed by the gases of both the hard coal and its own, thus effectively burning the fuel and economizing in 35 the quantity of consumption of the latter.

The deflectors are secured to the plates or walls 11 by being preferably cast with the same, and they are separate from the tubes 40 or flues 10, so that when the deflectors and plates require removal they may be drawn out of the furnace and fresh ones substituted therefor, the tubes or flues having been disconnected from the plates or walls 10, it 45 being evident that the latter when so disconnected may be removed for any purpose requiring the same and afterward restored or renewed by fresh tubes or flues.

Having thus described my invention what 50 I claim as new and desire to secure by Letters Patent, is:—

1. In a distributor for comminuted or pulverulent fuel for use in a furnace, deflectors, supports therefor, said deflectors being 55 spaced apart forming passages for the trav-

erse of the fuel therethrough and the discharge of the same in loose condition in various directions into the furnace, a supply hopper adapted to discharge into said chute and being in communication with said passages, a chute leading from said hopper into said distributor, and an air supplying device intermediate of said passages and hopper also in communication with said passages and terminating in a nozzle disposed 60 in said chute.

2. In a distributor for comminuted or pulverulent fuel for use in a furnace, deflectors, supports therefor, said deflectors being spaced apart forming passages for the traverse of the fuel therethrough and the discharge of the same in loose condition in various directions into a furnace, a supply hopper in communication with said passages, and a conductor for hot air adapted 70 to enter a furnace intermediate of the grate of the furnace and said deflector.

3. In a distributor for comminuted or pulverulent fuel for use in a furnace, deflectors, supports therefor, said deflectors being separated forming passages for the traverse of the fuel therethrough and the discharge of the same in loose condition in various directions into the furnace, a supply hopper in communication with said passages, a conductor for hot air adapted to enter a furnace intermediate of the grate thereof and said deflectors and a conductor for steam adapted 80 to enter the furnace and communicate with said passages.

4. In a distributor for comminuted or pulverulent fuel for use in a furnace, deflectors and supporting plates therefor, said deflectors being fitted between said plates and spaced apart forming passages for the traverse therethrough of the fuel, and water jackets on said plates, the latter being connected by tubular members which are in communication with said jackets and permit water to flow from one to the other.

5. In a distributor for comminuted or pulverulent material for use in a furnace, spaced apart deflectors, top and bottom plates, sleeves on said deflectors, and connections passed through said sleeves and having their ends secured to said top and bottom plates.

DANIEL GOFF.
